UNITED STATES PATENT OFFICE.

WILLIAM S. HODGES, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

AXLE-BOX.

1,114,474.

Specification of Letters Patent. Patented Oct. 20, 1914.

Application filed April 30, 1913. Serial No. 764,599.

To all whom it may concern:

Be it known that I, WILLIAM S. HODGES, a citizen of the United States, residing in Philadelphia, county of Philadelphia, State of Pennsylvania, have invented certain Improvements in Axle-Boxes, of which the following is a specification.

My invention relates to certain improvements in axle boxes for the driving wheels of locomotives, although the box can be designed for use on other vehicles without departing from the essential features of the invention.

The object of the invention is to construct the box so that it can be removed from the pedestals without having to jack up and remove the axles and wheels, as well as the boxes. This object I attain by making one of the flanges of the box detachable, as fully described hereinafter, reference being had to the accompanying drawing, in which:—

Figure 1, is a front view of an axle box illustrating my invention; Fig. 2, is a sectional view on the line *a—a*, Fig. 1, showing the detachable flange in position; Fig. 3, is a side view of the axle box, showing the detachable flange removed and in section; and Fig. 4, is a plan view, showing the detachable flange removed.

Referring to the drawing, 1 is the axle box having an opening 2 therethrough for the reception of the axle. At one end of the box is a fixed flange 3 formed in the ordinary manner, and at the other end of the box is a reduced segmental extension 4 having lugs 5; the rear edge of each lug being slightly beveled, as illustrated in Fig. 4.

6 is the detachable flange having an opening for the axle and shaped to fit the segmental portion 4 of the box, this detachable flange has inwardly projecting lugs 7, which normally rest back of the lugs 5 on the portion 4 of the box. The lugs 5 and 7 are so spaced that when the flange 6 is turned in one position the lugs 7 are opposite the spaces between the lugs 5, so that the flange can be placed on the portion 4 of the box. Then, by turning the flange 6, the lugs 7 travel back of the lugs 5. The lugs 7 are slightly tapered, as well as the lugs 5, so that when the flange is in the proper position, illustrated in Figs. 1 and 2, it is firmly secured and is prevented from rattling by the tight fit of the lugs.

The bottom of the box, as well as the base

of the removable flange is open, as illustrated, to receive the cellar 8 which contains the lubricant and when this cellar is in position it locks the detachable flange to the box, thus preventing it from turning in either direction. In order to hold the cellar in position, transverse bolts 9 are used, one of which passes through lugs 10 on the box and through lugs 11 on the cellar, while another bolt passes through lugs 12 on the detachable flange, and another through the lugs 11 on the cellar, as shown in the drawing. The bolts are held in position by keys or other fastenings.

It will be seen that by the use of an axle box of the construction above described on a locomotive where the driving wheels are on the outside of the frame, when it is desired to remove the box all that is necessary is to withdraw the bolts, detach the cellar and turn the detachable flange until the lugs on the flange are opposite the space between the lugs on the box, after which the flange can be detached and, when necessary, the box can be removed from the pedestal. The box can be readily applied by simply reversing the operation. In removing the box I preferably slide the box inwardly on the axle and then allow the flange to drop down.

I claim:—

1. The combination of an axle box having a fixed flange at one end and a detachable flange at the opposite end, the box and the detachable flange having spaced interlocking lugs so that when the detachable flange is turned the lugs will be free or will interlock; and means for holding the flange in the locked position.

2. The combination in an axle box having a fixed flange at one end and a segmental extension at the opposite end, said extension having external lugs spaced apart; with a detachable flange arranged to turn on the segmental extension and having internal lugs spaced apart so that, when the flange is turned into position, the lugs of the flange will be back of the lugs on the extension of the box; and means for locking the flange in position.

3. The combination of an axle box having a flange at one end and a segmental extension at the other end; external lugs on the extension; a detachable flange arranged to turn on the extension and having spaced

lugs engaging the lugs on the box when the flange is turned into position; with a cellar mounted in the box and locking the flange in position; and means for holding the cellar in the box.

4. The combination of an axle box having an opening for the axle and having a fixed flange at one end, said box having an opening at the bottom; a reduced portion; spaced internal lugs thereon; a detachable flange having internal spaced lugs and open at the bottom, the detachable flange being arranged to turn on the reduced portion, both

sets of lugs being tapered; a cellar adapted to the openings in the box and in the detachable flange; perforated lugs on the box, on the flange, and on the cellar; and a bolt extending through the lugs and holding the several parts in position.

In testimony whereof, I have signed my name to this specification, in the presence of two subscribing witnesses.

WILLIAM S. HODGES.
